(57) **CLAIM**

The ornamental design for a karaoke machine, as shown and described.

DESCRIPTION

FIG. 1 is a top, front and right side perspective view of a karaoke machine showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the portion labeled 9 in FIG. 1; and,

FIG. 10 is an enlarged detail view of the portion labeled 10 in FIG. 1.

The broken lines shown in the drawings illustrate portions of the karaoke machine that form no part of the claimed design. The dot-dash broken lines indicate cutoff boundaries for enlarged detail portion views and form no part of the claim.

1 Claim, 10 Drawing Sheets
